UNITED STATES PATENT OFFICE.

DON DAVID MILES, JR., OF SAN FRANCISCO, CALIFORNIA.

STARTING DEVICE FOR INTERNAL-COMBUSTION ENGINES.

1,160,521.

Specification of Letters Patent. Patented Nov. 16, 1915.

Application filed June 19, 1914. Serial No. 846,180.

To all whom it may concern:

Be it known that I, DON DAVID MILES, Jr., a citizen of the United States, residing in the city and county of San Francisco and 5 State of California, have invented certain new and useful Improvements in Starting Devices for Internal-Combustion Engines, of which the following is a specification.

This invention relates to an improvement 10 in starting devices for internal combustion engines.

The primary object of the present invention is to improve the construction and arrangement of the starting mechanism shown 15 in my copending application Serial No. 768,735, filed May 20, 1913, allowed April 16, 1914, particularly with regard to the actuating and controlling mechanism for the air distributor.

20 A further object of the invention is to provide means for opening the gas inlets of the cylinders to their full extent prior to the supplying of the gas thereto.

Another object of the invention is to so 25 construct the actuating means that the movement of one operating member will consonantly open the gas inlets of all of the cylinders and supply gas to one of the same, the supplying of the gas being delayed until 30 the gas inlets are completely open.

A still further object is to improve the construction of the distributing mechanism whereby to facilitate the operation of said mechanism and allow for the more ready 35 positioning of the distributing mechanism on the vehicle on which the motor to be started is mounted.

In the drawings: Figure 1 is a plan view 40 of an engine with my improvements applied thereto; Fig. 2 is a side elevation of the distributor with parts shown in section; Fig. 3 a sectional view thereof taken on the line through two of the piston chambers; Fig. 4 is a view of the distributor plate; Fig. 4¹ is a side elevation of the distributor looking at the opposite side to that of Fig. 2; Fig. 5 is a top plan view of the same; Fig. 6 is a top plan view of the distributor disk; Fig. 7 is a longitudinal sec- 45 tional view therethrough; Fig. 8 is a view partly in section of one of the angle cocks; Figs. 9 and 10 are views of the actuating mechanism; and Fig. 11 is a sectional view 50 through a portion of said mechanism illustrating the valves used therewith.

In the drawings, it will be observed that

while a four cylinder motor is illustrated it will be understood that by modifying the construction of the apparatus the same is applicable to motors having more than four 60 cylinders.

In most of the motors now in use on motor vehicles, each cylinder is provided with a priming opening but where the device is attached to a motor not provided with priming 65 openings each cylinder is tapped whereby access may be had to the interior thereof to receive gas therefrom, supply gas thereto and relieve compression. The cylinders are designated A, B, C, and D and mounted 70 upon the cylinder A and in communication with the interior thereof through the priming opening is a valve 11 which forms the subject matter of my copending application Serial No. 842,303 filed June 1, 1914. The 75 function of this valve is to periodically (that is with the firing of the cylinder A) supply gas under pressure to an outlet tube 12 which is connected in any suitable manner with a storage reservoir 13. The storage 80 reservoir may be mounted upon any convenient portion of the motor vehicle, preferably on the running board thereof. The valve is of such construction whereby back pressure from the reservoir will close 85 the same but not act to retard the supply to the reservoir except when a predetermined pressure, for instance, 250 pounds has been accumulated in the reservoir. While the motor is running the required pressure is 90 stored in the reservoir and is maintained after the engine is shut down.

A distributor 14 is supported adjacent the motor, the same being illustrated in the drawing as mounted upon a strap 15 secured to the frame 16 of the vehicle. This distributor 14 operates in substantially the same manner as the distributor illustrated in my co-pending application above mentioned, that is, the same upon the actuation 100 of a suitable valve supplies gas under pressure to one cylinder and relieves pressure in the cylinder on cylinders next in the order of firing. The distributor consists of a body portion 17 which is preferably die cast and 105 which is formed with the central bore 18 to receive the actuating shaft 19, the bore being increased in diameter as at 20 to accommodate the actuating cap 21 which is mounted on the shaft 19.

The disk 17 is formed with four radially extending chambers 22, 23, 24 and 25

These chambers, it being understood that four chambers are used in connection with a four cylinder motor, communicate with the bore 20 at their inner ends and at their outer ends with an annular channel or passage 26 formed in the periphery 27 of the disk 17.

The face 28 of the disk 17 is provided with four elongated slots 29, 30, 31 and 32.

10 These slots are of a length equal to the diameter of the radially extending chambers and the slots open into said chambers providing an outlet for the chambers, the function of which will be hereinafter described.

15 The opposite face 33 of the disk is provided with four elongated slots 34, 35, 36 and 37 which also are of a length equal to the diameter of the radial chambers. The last mentioned slots communicate with the chambers but at a point out of alignment with the slots 29, 30, 31 and 32, that is, the slots formed in the face 33 are disposed at a point adjacent the periphery of the disk 17 whereas the first mentioned series of slots are disposed nearer to the boss 38 of the disk.

The structure thus far described constitutes the body portion of the distributor.

20 As before stated the periphery of the disk 17 is provided with an annular gas channel 26. A ring or band 39 embraces the periphery of the disk being secured in position in any suitable manner, it being understood that gas cannot escape from the channel 26 between the disk and said ring. The ring 39 is formed with a tubular boss or extension 40 which communicates with the channel 26 and which is preferably threaded to receive 25 a plug 41 to which a suitable coupling 42 is connected. This coupling is connected to a supply tube 43 which communicates with the storage reservoir in a manner which will be hereinafter described. The supply of gas through the supply tube 43 being valve controlled whereby the same may be fed to the channel 26 when it is desired to start the motor.

25 Fitted upon the disk 17 is the distributor plate 44 its face, which is opposed to the disk being flat, particular reference being had in this connection to Fig. 3 of the drawings. The distributor plate is formed on its face remote from the disk and adjacent its periphery with an enlargement 45 in which is formed four by-passes or passages, A', B', C', and D', corresponding to the cylinders A, B, C and D. The passage A' passes entirely through the plate its outlet 30 through the flat face 47 of the plate communicating with the slot 37 in the face 33 of the disk 17 whereby the passage A' communicates with the chamber 23 of said disk. The passages B' and C' extend across the flat face 47 of the distributor that is they not

merely open through the plate as do the passages A' and D', their outlets being disposed adjacent the lower edge of the plate whereby they may communicate respectively with the slots 35 and 34 of the disk, it being understood that the passage D' communicates with the slot 37. By this construction it will be noted that each of the passages communicate with one of the radial chambers of the disk. A threaded tube 48 is inserted within each of the passages and connected to each of said threaded tubes is a coupling 49. There are four tubes provided which communicate with the four couplings and each of these tubes are connected to an angle cock 50 the extension 51 of which projects within the priming opening of one of the engine cylinders whereby communication is established between each passage way of the distributor plate and a cylinder of the motor. The plug 52 of the cock is manipulated to open and close the passage through the same by means of a link 53 the links of the four cocks being connected by a rod 54. It will be understood that while the cylinder which receives the valve 11 is not provided with identically the same form of cock which is inserted in each of the other cylinders, the passage through the lower stem of the valve which is inserted in the cylinder is controlled by a plug operated by a link connected to the actuated rod 54. It will therefore be seen that by manipulating the actuating rod 54 in one direction that all of the angle cocks will be opened to permit the free passage of gas to the cylinder or of the relieving of the cylinders.

The distributor plate 44 is secured to the disk 17 by a plurality of screws which pass through the openings 55 in the plate and extend within threaded openings formed in the disk. The shaft 19 on which the actuating cam 21 is mounted may be driven in several different ways, that is, it may be mounted directly on the timed shaft 56 as shown in the drawing, or upon the cam shaft, or in fact the cam may be rotated in any suitable manner it being understood of course, that the same must rotate in proper timed relation with the engine.

115 Mounted within each of the radial chambers of the disk 17 is a piston 57 which is of a length less than the distance between the bore 20 and the inner face of the annular member 39 whereby the pistons may be actuated and travel within said cylinders to perform their function which will be hereinafter described. Each piston is provided with a portion 58 of a diameter slightly less than the diameter of the chamber and this portion 58 is recessed to accommodate a split resilient piston ring 59, the piston ring 59 snugly engaging the walls of the chamber whereby gas may not pass around the piston to the bore 20. The pistons are provided 120

with reduced rounded ends 60 which project within the bore 20 when gas is introduced in the annular passage 26. The piston is reduced intermediate its ends to form an annular channel 61 by means of which the connections from the cylinders may be brought into communication with the atmosphere to relieve the cylinders through the elongated slots 29, 30, 31 and 32. Upon the introduction of gas from the reservoir to the annular channel formed in the disk the gas pressure will project each of the pistons inwardly toward the cam 21. The peripheral edge of the cam 21 is adapted to contact with the inner end of each of the pistons to force the same outwardly toward the annular ring 39. This peripheral face however, is of such a contour that while two of the pistons are completely extended toward the annular member 39 one other piston may be completely projected inwardly and the fourth piston projected inwardly sufficiently far to allow one of the cylinders of the engine to communicate with the atmosphere through one of the passages A', B', C' and D', through the annular channel 61 formed in the piston and one of the slots 29, 30, 31 and 32. The piston, which the inrushing gas has projected inwardly to its full extent establishes communication between the reservoir and one of the cylinders, the gas passing behind the projected piston to one of the passages of the distributor plate where it is supplied to the cylinder. Thus the cam at all times when the device is in operation is supplying gas to one cylinder and relieving compression in the cylinder which is next in the order of firing. The valves which control the angle cock, that communicates with the cylinders and the valve which controls the supply of gas from the reservoir to the distributor are controlled by the actuating mechanism shown in Fig. 10. This actuating mechanism consists of a plate 62 which is preferably secured to the dash board of the vehicle. Operating through this plate is a plunger 63 which is maintained extended by means of a coiled spring 64, the plunger being provided with an actuating head 65 for the operator's foot. This plunger is received within a barrel 66 which projects through the dash board, the barrel being double diametered, the coiled spring 64 contacting with the shoulder 67 formed by reducing said bore. The plunger projects through the reduced bore and its end portion is bifurcated receiving between its bifurcations the terminal of the link actuating rod 54. A set screw 68 passes through the bifurcations of the plunger and an aperture formed in the rod 54. A pin 69 passes transversely through the plunger and contacts with a washer 70, the pin preventing the spring 64 from drawing the plunger out of the barrel. A sleeve 71 extends

through the plate 62 and is threaded into the barrel 72 of the casting 73. The sleeve 71 supports the casting, the barrel 72 of which is provided with an inlet 74 and an outlet 75. A needle valve 76 extends through the sleeve 71 into the barrel 72 being provided with a conical head 77, the barrel being formed with a conical seat 78 to receive said valve. The inlet 74 of the barrel is connected to the tube which connects the cylinder of the engine with the reservoir. The casting 73 is provided with a branch 79 in which is arranged a by pass 80 whereby gas from the reservoir may pass through the inlet 74 around the valve and through said by-pass to a valve chamber 81 which is preferably formed integral with the branch 79 of the casting 72. In this valve chamber is arranged a plunger 82 which projects through the plate 62, its terminal 83 being disposed slightly beyond said plate and in the path of the head 65 of the plunger 63 which actuates the angle cocks. The plunger 82 is maintained with its end projected through the plate 62 by means of a coiled spring 84 which bears against a removable cap 85, said cap forming a closure for the valve chamber 81. The plunger is provided with a head 86, the chamber being cut to provide a seat 87 for said head. The spring 84 maintains the head 86 in contact with said seat whereby the passage of gas from the reservoir through the by-pass 80 is checked in the chamber. When the plunger is reciprocating against the tension of the spring 84 in a manner which will be hereinafter described, the head 86 is moved out of contact with the valve seat and the gases under pressure pass around the head and to an outlet 88 in the valve casing 81 to which is connected the tube 43. The gas passes through the tube 43 to the annular chamber of the distributor and projects the piston of said distributor inwardly in the manner heretofore described.

It will be understood that the pressure in the passage or inlet 74 is equivalent to that in the reservoir and under normal conditions the needle valve is open. A pressure gage 91 has its receiving stem threaded into the sleeve 71 whereby the pressure in the reservoir will be plainly indicated by the operator.

With the needle valve open and sufficient pressure in the storage reservoir, the plunger 63 is pressed toward the plate 62, its movement from its extended position to a point adjacent the terminal 83 of the plunger 82 being sufficient to manipulate the rod 54 to open all of the angle cocks to their full extend and thus establish communication between each cylinder and the distributor. The pressure on the head 65 is continued until the same contacts with the plunger 83 moving the same in the valve chamber over-

coming the tension of the spring 84 and unseating the head 86 whereby the gas under pressure will pass from the tank connection through the inlet 74 of the sleeve 72 around the valve 77 and through the passage 80 to the valve chamber 81. The gases then pass around the head 86 and through the outlet 88 of the valve chamber 81 to the tube 43 which is connected to the distributor. With the pressure still maintained on the plunger 63 the gas continues to flow under great pressure and thrust the pistons 58 inwardly in contact with the cam. The cam at the initial intake of gas to the distributor is idle, as is the motor and one of the pistons will therefore fall on the low face 92 of the cam. With one of the pistons in this position, gas from the annular channel of the disk passes in behind the same the piston being moved inwardly sufficient to uncover the slot formed in the disk adjacent its periphery, the gas passing through said slot to the tube with which it communicates. It will be understood that this elongated slot communicates with one of the connections A', B', C' or D' and that gas under pressure is thus supplied above the piston in one of the cylinders to exert pressure thereon to start the engine. Simultaneous with the applying of gas pressure in one cylinder the cylinder in the next order of firing is relieved through one of the outlets in the face 28 of the disk it being understood that when one of the distributor pistons has been projected inwardly to a point where it uncovers a delivery slot, another of the pistons will have been moved inwardly sufficient to bring one of the innermost or exhaust slots into communication with the annular channel of the piston and therefore the cylinder which is next in the order of firing is brought into communication with the atmosphere. As the shaft of the engine is "turned over" and the cam begins to rotate, the various pistons of the distributor operating in proper sequence will supply gas under pressure and relieve the compression in the various cylinders until the motor is running. When the motor has been started, pressure on the plunger 63 is relieved and the spring 64 allowed to bring the same to its normal position. As the head 65 of the plunger is brought out of contact with the plunger 82 the valve 86 will close, and the passage of gas to the distributor will be cut off.

Particular attention is called to the construction and operation of this controlling mechanism and the result accomplished thereby. By a single thrust of the actuating pedal the valves in the connections between the cylinders and the distributor are open to their full extent and held in open position, the same thrust which opens the valves consonantly establishing communication between the reservoir and the dis-

tributer, the arrangement being such that the action of opening the valve which admits gas to the distributor is delayed until all of the intake valves of the cylinders of the motor are completely open and ready to receive gas.

As before stated the operation of the distributor is substantially the same as that of the distributor in my co-pending application hereinbefore mentioned, but particular attention is directed to the specific form of cam whose peripheral face is of such a contour that the valve pistons of the distributor are not merely momentarily open, but their supplying and compression relieving action is so delayed that the proper supply of gas is fed to each cylinder in its order of firing and the proper relieving of each cylinder is accomplished. The configuration of the active face of the cam is such that it is spaced from the rounded ends of two of the pistons to an extent whereby complete relieving and supplying of each cylinder is accomplished in proper sequence. Thus the present invention distinguishes clearly from such devices in the art as cause a momentary opening and closing of the inlet ports of the engine and the advantages of the present device over the prior art in this connection it is thought will be apparent.

I claim:

1. A starting device for internal combustion engines and in combination with the engine cylinders thereof, the same comprising a storage reservoir, a valued connection between an engine cylinder and the reservoir whereby the engine on its firing stroke will cause a portion of the burnt gases to pass to the reservoir, a pressure controlled distributing member receiving the gas from the reservoir, a valve controlling the supply of pressure to said distributing member, connections between said distributing member and the cylinders, valves in said connections, means for opening the valves in said connections and subsequently actuating the first mentioned valve to supply gas to the distributing member, said distributing member including independently operable means for consonantly supplying the pressure to one cylinder and relieving the compression in the cylinder which is next in the order of firing.

2. A starting device for internal combustion engines and in combination with the engine cylinders thereof, the same comprising a storage reservoir, means for supplying the burnt gases from one of the engine cylinders to the reservoir under pressure, a distributing member, means controlling the supply of gas from the reservoir to the distributor, connections between the distributing member and the engine cylinders, valves arranged in said connections, means for opening said valves and thereafter op-

erating the valve which controls the supply of gas to the distributor, the distributor including independently operable means for supplying gas admitted thereto directly to each of the cylinders in their order of firing, and means for establishing communication between each cylinder independently of the remaining cylinders and the atmosphere through the distributing member

5 when the piston in said cylinder is on its stroke prior to its firing stroke.

3. In a starting device for internal combustion engines and in combination, a series of engine cylinders, a storage reservoir, a valve connection between one of the cylinders to the reservoir whereby upon the firing of the charge in the cylinder a portion of the gases are caused to pass to the reservoir, a connection between the reservoir and the cylinder for supplying the gases directly to the cylinders above the pistons, combined supply and exhaust valves for each of the cylinders located in the connection between the reservoir and the cylinders, said valves 20 being controlled by the pressure from said reservoir, valves controlling the admission of gas to the cylinders, a valve controlling the supply of gas from the reservoir to the connection between the reservoir and the cylinders, and a member having an operative connection with said valves for consonantly operating the same whereby the valves of the cylinders are opened in advance of the valve in the connection between the reservoir and the cylinders.

4. A starting device for internal combustion engines and in combination with the engine cylinders thereof, the same comprising a storage reservoir, means for supplying the burnt gases from the engine cylinder to said reservoir under pressure, a pressure controlled distributing member, a connection between the reservoir and the distributing member, a valve in said connection, connections between the distributing member and each of the cylinders, valves arranged in each of said connections, an actuating member having an operative connection with each of said valves, the initial movement of 45 said actuating member operating the valves in the connections to the cylinders, and a continued movement of said member opening the valve in the connection between the reservoir and the distributor.

5. A controlling mechanism for starters for internal combustion engines which include a gas storage reservoir, a connection between said reservoir, and one of the engine cylinders, a manually operated valve in said connection, said valve having a by-pass whereby when the valve is opened gas from the reservoir will be conducted past the valve, a conduit connected to the by-pass and receiving gas passing therethrough, means connected to the conduit for supply-

ing gas to each of the cylinders, inlet valves for each of the cylinders, a valve in said conduit, and means having an operative connection with the cylinder inlet valves for opening the same, said means when actuated causing the opening of the valve in the conduit, the opening of the first mentioned valve occurring after the cylinder valves are opened.

6. A controlling mechanism for starters of internal combustion engines, which includes a gas storage reservoir, a connection between said reservoir and one of the engine cylinders, a valve in said connection and a conduit communicating with said connection intermediate said valve and the engine cylinder, means connected to said conduit for supplying gas to each of the cylinders, a valve arranged in said conduit, inlet valves for the cylinders, a plunger having an operative connection with the cylinder inlet valves, and a member controlling the valve in said conduit, said member being disposed in the path of movement of said plunger whereby upon movement of the plunger on its valve opening stroke the inlet valves of the cylinder and the valve of the conduit will be opened, the opening of said inlet valves occurring in advance of the opening of the valve in said conduit.

7. A controlling mechanism for starters of internal combustion engines, which include a gas storage reservoir, a connection between one of the engine cylinders and said reservoir, a manually operated valve in said connection, a conduit leading from said connection from a point intermediate the valve arranged therein and the cylinder, a valve in said conduit, the conduit having a connection with each of the engine cylinders to supply gas thereto, inlet valves for the cylinders, and means for consonantly opening the inlet valves of the cylinders and the valve in said conduit.

8. A controlling mechanism for starters of internal combustion engines which include a gas storage reservoir, a connection between said cylinder and said reservoir for supplying gas under pressure to said reservoir, a valve in said connection, said valve being formed with an extension having a connection with the engine cylinders and constituting a by-pass whereby gas from the reservoir may be supplied to the cylinders, a valve controlling the outlet through said by-pass, valves controlling the inlets of the cylinders, and means for consonantly operating the cylinder valves and the valve arranged in the by-pass.

9. A controlling mechanism for starters of internal combustion engines which include a gas storage reservoir, a connection between said reservoir and one of the engine cylinders whereby gas under pressure from said cylinder will be supplied to the reser-

8
voir, a manually operated valve in said connection, a conduit receiving gas from the reservoir through said valve, a valve arranged in said conduit, means connected 5 with the conduit for supplying gas to each of the engine cylinders, valves controlling the inlet to said cylinders, and a member controlling said inlet valves, said member on its initial movement opening the inlet valves, 10 the continued movement of the member

operating the valve arranged in the conduit whereby gas is supplied to the cylinders.

In testimony whereof I have signed my name to this specification in the presence of two subscribing witnesses.

DON DAVID MILES, JR.
